OR D 13,034

DESIGN FOR A BURIAL-CASKET.

Design No. 13,034, dated July 11, 1882.

UNITED STATES PATENT OFFICE.

LEO STEIN, OF ROCHESTER, NEW YORK, ASSIGNOR TO THE STEIN MANUFACTURING COMPANY, OF SAME PLACE.

DESIGN FOR A BURIAL-CASKET.

SPECIFICATION forming part of Design No. 13,034, dated July 11, 1882.

Application filed May 19, 1882. Term of patent 7 years.

To all whom it may concern:

Be it known that I, LEO STEIN, of the city of Rochester, in the county of Monroe and State of New York, have invented or produced 5 a new and original Design for Burial-Caskets; and I do hereby declare that the following is a full, clear, and exact description of the same, reference being had to the accompanying photographic illustration, showing a perspective 10 view of the casket.

This design relates to cloth-covered burial-caskets; and it consists of a folding of cloth laid in plaits around the sides and ends of the casket and flowers arranged at intervals in 15 the folding, thereby presenting a pleasing external appearance.

In the illustration, *a a a* show a folding of cloth laid in several plaits, as shown, extending around the sides and ends of the casket.

20 *b b b* are flowers arranged at intervals in the folding and being attachments to the same.

c is a lace border above and below the folding, extending all the way around. The folding makes an ornament to the casket and 25 relieves the plainness of the sides. The flow-

ers, arranged at intervals, serve to break the monotony of the folding and to divide it into sections. The whole presents a pleasing external appearance.

What I claim as new, and desire to secure 30 by Letters Patent, is—

1. The design for a burial-casket, consisting of the folding *a a a*, laid in plaits on the exterior surface of the casket, and flowers *b b b*, arranged at intervals in the folding, as herein 35 shown and described.

2. The design for a burial-casket, consisting of the folding *a a a* on the exterior surface of the casket, the flowers *b b b*, arranged at intervals in the folding, and a lace border, *c c*, 40 above and below the folding, as herein shown and described.

In witness whereof I have hereunto signed my name in the presence of two subscribing witnesses.

LEO STEIN.
